(57) **CLAIM**

We claim the ornamental design for wrench set case, as shown and described.

DESCRIPTION

FIG. 1 is a perspective view of the front of the wrench set case;

FIG. 2 is a perspective view of the rear of the wrench set case;

FIG. 3 is a top view of the wrench set case;

FIG. 4 is a left hand side view of the wrench set case;

FIG. 5 is a front view of the wrench set case;

FIG. 6 is a rear view of the wrench set case;

FIG. 7 is a right hand side view of the wrench set case;

FIG. 8 is a bottom view of the wrench set case; and,

FIG. 9 is a perspective view of the wrench set case with the containers removed.

The design is the external appearance of the wrench set case as shown in the drawings.
